MANDREL

Earl B. Newell, St. Paul, Minn.

Application September 16, 1938, Serial No. 230,256

2 Claims. (Cl. 242—72)

This invention relates to a collapsible and expandable mandrel useful for a number of purposes but particularly adaptable for use in the cores of paper rolls such as used in the newspaper industry.

An object of the invention is to provide an improved and simplified yet highly efficient mandrel of the class described.

This mandrel is tubular and preferably made of two longitudinally registering sections and a central shaft to simultaneously manipulate a plurality of expansion members, two of said members located at the respective ends and bored to provide bearing means engaging the roller spindles of a printing press. Extreme simplicity and efficient action are stressed, reference being had to the accompanying drawing; in which—

Fig. 1 is a longitudinal, diametrical section illustrating a mandrel constructed in accordance with a preferred embodiment of my invention.

Fig. 2 is a left end elevation of Fig. 1.

Fig. 3 is an enlarged sectional view taken substantially on the line 3—3 of Fig. 1.

Referring to the drawing by reference numerals, like characters designating corresponding parts in the various views; in the preferred embodiment of the mandrel it is tubular comprising two registering, opposite semi-tubular sections designated 4 and 5, normally with edges contacting when the mandrel is adjusted to minimum size. 6 is a two part flange fixed at one end of the mandrel one part on each mandrel section, said flange parts keyed together slidably, as with a pair of dowel pins 7 which serve to hold the end parts in proper relation when the mandrel is expanded.

At and within each of the end parts of the mandrel is centrally and reciprocally retained a combination cone and bearing member tapering inwardly, the right hand cone designated 8R and the left hand one 8L, the latter at the flanged end of the mandrel. Both these cones have outwardly open bores 8B their inner ends being closed. The said end cones are connected centrally and manipulated by a central bar 9 rotatably retained in the inner closed end of the cone 8R but the inner end of cone 8L is threaded to receive the correspondingly threaded part 9T of the bar or shaft 9 which projects into the bore 8B of said cone 8L and its end is of polygonal form as at 9P. This end part 9P is of course easily accessible for engagement by a socket wrench (not shown).

Each cone (8R—8L) is in contact exteriorly with a pair of arched segments 10, one fixed in

each mandrel section 4—5, diametrically of each other, each said pair of segments having inwardly tapered faces. 10A in Fig. 1 designates an intermediate set of arched segments of which there may be two or more sets, each engaged by a cone 5 8 rotatably engaged centrally by the adjustment shaft 9 in the same manner as cone 8R. A preferred method of rotary engagement of shaft 9 in cones 8 and 8R is the provision of a pair of collars 11 which are properly spaced and retained on the 10 shaft as with a cotter key 12.

13R and 13L designate, for example only, a pair of spindles as of a printing press and rotatably engaging respectively the bores of the cones 8R and 8L. 16 designates in dotted outline a roll 15 of news print paper in the core or central bore of which my device is inserted while contracted.

14 are a number of transverse webs in the mandrel each comprising two registering parts one part fixed in each mandrel section. The central 20 part of each web has a bore 14B for allowing passage of the shaft 9 freely therethrough. The said webs are provided with two pairs of horizontally disposed lugs 14L, a pair at each side of the bore and spaced apart vertically (see Fig. 3). 25

In each such pair of lugs, one lug is threaded and the other has a registering bore for insertion of a machine bolt 15 through the latter and into the threaded lug. When positioned, such bolts each has its head in spaced relation to the adjacent lug as shown thus limiting the amount of spreading or expansion of the mandrel, yet holding the mandrel sections together at all times. These lug members need only be on the web members 14 nearest the ends of the mandrel and 35 are accessible for adjustment (by the bolts 15) when the cones and shaft are not in place.

In contracted or what may also be termed collapsed condition the mandrel is of minimum size, the edges of the main sections being in contact 40 and the cones 8 and 8R are separated from cone 8L to about the limit permitted by the threads 9T. In this condition the mandrel is slidably inserted in the central bore of a paper roll 16 until flange 6 contacts one end thereof. Then 45 inserting an end-socket wrench in the bore of cone 8L and engaging the end of the rod 9 the latter is rotated simultaneously drawing the cones 8 and 8R toward cone 8L and all the cones simultaneously engaging the segments 10 and expanding 50 the mandrel uniformly throughout its entire length. The amount of expansion required is usually not great, for the use described, the paper roll is securely engaged and the roll is ready for mounting in a press as shown. 55

A feature of my improved mandrel is its extremely simple construction involving the least possible number of parts all readily assembled and adjusted.

5 Modifications within the scope and spirit of the invention and the claims may be made it being understood that I do not wish to limit myself to the precise arrangement and formation of the parts shown and described.

10 I claim:

1. A tubular expandable mandrel comprising a plurality of elongated sections adapted to contact edge to edge when the tube is collapsed, a sectional exterior flange on said tube at one end thereof, an expansion device within said tube comprising a central rotatable shaft, an inwardly tapering cone member on the shaft one in proximity to each end of the mandrel, an intermediate cone member on said shaft and rotatably mounted thereon, a group of inwardly directed fixed segments in said mandrel sections for each cone and having tapered faces corresponding to the faces of said cones and contacted thereby, said shaft threaded at one end and engaging corresponding threads in an end cone the extreme end of said threaded part accessible for engagement to rotate the shaft and simultaneously draw all the cones into sliding contact with said segments and expand the mandrel uniformly throughout its entire length, said end cones pro-

vided each with a central bore opening outwardly at its larger and exterior end to provide a spindle journal.

2. A tubular, expandable mandrel comprising a plurality of elongated sections adapted to lie in contact edge to edge when the mandrel is contracted, a sectional exterior flange on said tube at one end, an expansion device within the tube comprising a central rotatable shaft, an inwardly tapering cone member on said shaft one in proximity to each end of the mandrel, an intermediate cone member on said shaft and rotatably mounted on the latter, a group of inwardly exposed, fixed segments in said mandrel sections for each said cone member and having tapered faces corresponding to the faces of said cones and contacted thereby, said center shaft threaded at one end and engaging corresponding threads in an end cone the extreme end of said threaded part accessible for engagement to rotate the shaft and draw all the cones into simultaneous sliding contact with said segments to expand the mandrel uniformly throughout its length and a number of spaced transversely positioned sectional wall members within the mandrel and adjustable means connecting the adjacent parts of said wall members, to retain them in proper registering positions and simultaneously limit the spreading of the mandrel sections.

EARL B. NEWELL. 30
